UNITED STATES PATENT OFFICE.

JOHN A. LAWSON, OF HARDIN, MISSOURI.

HEADER-BOX.

1,239,408.

Specification of Letters Patent.

Patented Sept. 4, 1917.

Application filed August 8, 1916. Serial No. 113,807.

To all whom it may concern:

Be it known that I, JOHN A. LAWSON, a citizen of the United States, residing at Hardin, in the county of Ray, and State of Missouri, have invented new and useful Improvements in Header-Boxes, of which the following is a specification.

This invention is an improved header box adapted to be arranged on the running gear of a wagon and used in hauling wheat from the header in the field, to the stack and for depositing the wheat on the stack, the object of the invention being to provide an improved header box of this kind which is cheap and simple in construction, which may be made principally of sheet metal, which is light, strong and durable and which can be readily disassembled and compactly arranged for storage.

The invention consists in the features of construction, combination, and arrangement of devices, hereinafter fully described and claimed:

In the accompanying drawings:

Figure 1 is a side elevation of a header box constructed and arranged in accordance with my invention.

Fig. 2 is a vertical transverse sectional view of the same.

Fig. 3 is a vertical longitudinal sectional view of the same.

Fig. 4 is a detailed sectional view on the plane indicated by the line 4—4 of Fig. 1.

Fig. 5 is a similar view on the plane indicated by the line 5—5 of Fig. 1.

Fig. 6 is a detailed horizontal sectional view taken on the plane indicated by the line 6—6 of Fig. 3.

Fig. 7 is a detailed transverse sectional view of the same on the plane indicated by the line 7—7 of Fig. 1.

The bottom 1, sides 2, 3, and ends 4, 5, of my improved header box are in practice constructed of sheet iron of suitable gage.

The bottom 1 is arranged between a pair of longitudinal tubular bars 6, 7, and is secured to said bars by sheet metal straps 8. Said sheet metal straps are doubled as shown, extend around the bars and are arranged on and secured to the upper and lower sides of the bottom and hence serve to not only connect the bottom to the bars, but also serve to materially brace and strengthen the bottom as will be understood.

The side 2, which I will call the front side, is formed with a lower inturned por-

tion 9 which in effect is a lateral extension of the bottom and is detachably connected to the tubular bar 6 by means of doubled sheet metal straps 10 which are riveted to the said side 2 as shown. The said side 2 is also formed with wheel boxes 11 which are made of sheet metal and which are detachably secured to the tubular bar 6 by straps 12 that are similar in construction to the straps 10.

The side 3 of the header box, which I will call the rear side, is connected detachably to the bar 7 by doubled sheet iron straps 13 and which serve to brace and strengthen the lower vertical portion 14 of said side. The upper portion of said side is inclined outwardly and upwardly. At the upper side of the side wall 3 is an extension 15 which is also made of sheet iron and which is hinged and detachably connected to the side wall 3 by doubled sheet metal straps 16, 17, which are respectively attached to the side wall 3 and the extension 15, by means of rivets and a pivotally mounted rod 18 which extends through the cylinder, or tubular portions of said straps as shown. Hence the extension 15 may be extended upwardly from the side wall 3 and substantially in line therewith or may be inclined inwardly over the box and somewhat lowered thereon, as indicated in dotted lines in Fig. 2, as when a strong wind is blowing.

A tubular bar 19 is secured in a roll 19 at the upper edge of the side wall 2 and a similar tubular bar 20 is secured to the upper edge of the extension 15 by doubled sheet iron straps 21.

Brace rods 22 which are bent as shown, have their lower ends passed through openings in the tubular bar 6 and are provided with securing nuts 23, said bent brace rods passing upwardly through the wheel boxes and their upper ends passing through the bar 18, and roll 19 and being provided with nuts 24.

The front end 4 is shaped to fit between the bottom and the side walls as shown, has its lower end secured to the bottom by an L-bar 25 and a bolt 26 or the like and has its upper portion secured between the sides 2, 3, by a rod 27 which is hooked to the rod 17 and passes through an opening in the rod 18 and is provided with a nut 29, said rod being secured on said front end wall of the box by means of straps 30. The front ends of the tubular bars 6, 7, project for-

wardly of the box. A seat 31 for the driver is secured on the end 4 by angle irons 32 which also form legs and having their lower ends bent and extended into and secured in the front ends of the tubular bars 6, 7, said legs or angle irons being provided with offset doubled portions 33 between which are secured the ends of a step 34.

Brace rods 36 are provided for the extension 15 and have their upper ends passed through openings near the ends of the tubular bar 20 and secured by nuts 37. When the extension 15 is in nearly vertical position, substantially in line with the side wall 3, the lower portions of the brace rods 36 are secured in openings in the tubular bars 7 by means of nuts 38. In order to adjust the extension 15 to a lower position, inclined inwardly over the header box, as when a strong wind is blowing, the brace rods 36 are disconnected from the tubular bar 7 and their lower ends are passed through openings in the tubular bar 6 and secured to said bar by nuts 38. Hence the extension may be secured in either adjusted position at will. When the extension is in the position shown in full lines in Figs. 1, 2, and 3, the rear brace rod 36 is engaged by an arm 39 of the rod 17. Said rod is movable longitudinally through the strap connections between the wall 3 and extension 15, to enable its arm 39 to be engaged with or disengaged from said brace rod 36 as may be required. The rear end of the gate 5 of the header box is pivotally mounted on a brace rod 40 which is similar to the rod 27 and has its upper portion hooked to the rod 17 and its lower outer end passed through an opening in the rod 18 and provided with a nut 41. The end or 40 gate 5 may be opened or closed as required in the use of the header box and when closed is secured in such position by a bolt 42 which engages with an opening in the rear end of the bottom.

45 The header box is mounted on the running gear 43 of an ordinary farm wagon, its bars 6, 7, bearing on wooden bars 44 arranged across the bolsters and being clamped to said bars 44 by means of clamping devices 46 and bolts 47 with which the bars 6, 7, of the header box are provided. The header box may be readily removed from the running gear when desired.

To assist in counterbalancing the header box, when the same is being unloaded and the wheat is being dropped onto a stack, I provide a U-shaped hanger step 48 which is secured to and depends from the center of the side wall 2 and on which a man may step when the header box is being unloaded so that his weight may be utilized in counterbalancing the header box.

In connection with the header box, a canvas apron 49 is employed which is sufficiently large to cover the inner surfaces of

the side walls and extension 15 of the header box and to also extend across the bottom thereof to receive the load of wheat or headed grain placed in the header box, from the heading machine. This apron is provided at two of its corners with hooks 50 to engage the bar 20. A stiffening rod 51 is secured in the opposite, free end of the apron. Hooks 52 are employed at the front corners of the apron to engage over the roll 19 and secure the front or free end of the apron on the upper edge of the wall 2 and permit its ready detachment therefrom and at the center of the front edge of the apron is a ring 53 for the attachment of a pull rope 54 which is employed to pull the apron, together with the load of headed grain in the box, over the wall or side 3 and discharge the same onto a stack, as indicated in Fig. 3. A horse, or any suitable power, may be employed for thus unloading the header box, and depositing its load on the stack.

By first removing the bars 6, 7, 20, and the brace bars 22, 36, and rods 27 and 40, the sides, bottom, and ends of the header box may be readily disconnected and all the parts of the header box may be compactly arranged for storage, so that the header box will occupy but little space, when not in use.

My improved header box thus constructed, is light as compared with those heretofore used, and may at the same time be made of greater capacity so that the header box may be more easily handled and the labor of the team lessened.

Having described the invention, what is claimed is:

1. A header box comprising sheet metal side walls, a sheet metal bottom, a pair of longitudinally arranged bars and doubled sheet metal straps on the bottom and side walls, said straps bracing the bottom and side walls and also engaging the bars and attaching the bottom side walls to the bars, one of the side walls being provided with an in-turned portion forming a lateral extension of the bottom, and brace rods passing through said lateral extension and attached at their lower ends to one of the bars and at their upper ends to the upper end of said side wall.

2. A header box comprising a bottom, side walls, an extension at the upper side of and pivotally connected to one of said side walls, a pair of longitudinal bars to which the bottom and side walls are connected, and brace rods connected to the extension and adapted to be attached to either of said bars to secure the extension in either adjusted position.

3. A header box comprising a bottom, side walls, an extension at the upper side of and pivotally connected to one of said side walls, a pair of longitudinal bars to which the bottom and side walls are connected,

and brace rods connected to the extension and adapted to be attached to either of said bars to secure the extension in either adjusted position, said side wall and extension having a movable pivotal member adapted to be engaged with and disengaged from one of said brace rods.

4. A header box having side walls of unequal height, an apron attached to the upper side of the higher side wall, and a step 10 attached to and depending from the lower side wall.

5. A header box comprising a bottom, side walls of unequal height, a pair of longitudinal bars to which the bottom and side walls are connected, a bar in the upper side of the lower side wall, an extension at the upper side of the higher side wall and pivotally connected thereto, a bar at the upper 15 side of the extension, brace rods connected to the last-named bar and adapted to be attached to either of the first-named bars, front and rear end walls, brace rods for said front and rear end walls, each connected to said pivotal member and also connected 20 to the said bar at the upper side of the lower side wall, the rear end wall being pivotally mounted on its said brace rod and being provided with securing means.

nected to the said bar at the upper side of the lower side wall.

6. A header box comprising a bottom, side walls of unequal height, a pair of longitudinal bars to which the bottom and side 30 walls are connected, a bar in the upper side of the lower side wall, an extension at the upper side of the higher side wall and pivotally connected thereto, a bar at the upper side of the extension, brace rods connected 35 to the last-named bar and adapted to be attached to either of the first-named bars, front and rear end walls, brace rods for said front and rear end walls, each connected to said pivotal member and also connected 40 to the said bar at the upper side of the lower side wall, the rear end wall being pivotally mounted on its said brace rod and being provided with securing means.

In testimony whereof I affix my signature. 45

JOHN A. LAWSON.
